UNITED STATES PATENT OFFICE

118,261

DESIGN FOR A MINE LOCOMOTIVE

Henry Fort Flowers, Findlay, Ohio

Application October 10, 1939, Serial No. 87,615

Term of patent 14 years

To all whom it may concern:

Be it known that I, Henry Fort Flowers, a citizen of the United States, residing at Findlay, in the county of Hancock and State of Ohio, have invented a new, original, and ornamental Design for Mine Locomotive, of which the following is the specification, reference being had to the accompanying drawing, forming a part thereof.

In the drawing:

Figure 1 is a perspective view looking toward the front and left side of the mine locomotive showing my new design

Figure 2 is a perspective view looking toward the rear and left side of the mine locomotive, showing my new design,

Since the right side of the mine locomotive is the same in appearance as the left side, illustration other than that provided in Figures 1 and 2 of the drawing is thought to be unnecessary.

I claim:

The ornamental design for a mine locomotive, as shown and described.

HENRY FORT FLOWERS.
